UNITED STATES PATENT OFFICE.

EARNEST A. BACON, OF STILLWATER, MINNESOTA.

FUSE-CLIP CLAMP.

Application filed November 10, 1924. Serial No. 748,883.

My invention relates to clamps which are particularly adapted to be attached to fuse clips so as to hold the free ends of the arms of the clip tightly over the end of the fuse 5 engaging in the clip so that no arcing or heating of the fuse will take place.

The invention includes means for holding the operating members of the clamp in a manner so as to insulate the operating end 10 of the clamp sufficiently so that the operator's fingers will not come in contact with the electrical connections or with the metallic parts of the clamp itself. To accomplish this I provide a flange formed of insulating 15 material which projects sufficiently to cover the operating members and form a shoulder against which the ends of the fingers of the operator rest when the operating cap or head is engaged and thus insure the easy 20 attaching or disengagement of the clamp from the fuse clips.

It is also a feature of the invention to provide an operating member wherein the engaging end is formed integral with the operating cam, which is also formed of insulating material, and is provided with a slightly bevelled edge to the cam so as to provide a construction wherein the engagement of the cam with the operating arms 25 of the clamp is held in close proximity to the operating arms by the lugs which engage the bevelled surface of the cam.

A further object of the invention is to provide spacing lugs which are formed to engage with the ends of the clamping fingers so that the clamp may be attached either to a wide opening or a narrow opening, such as is true of a knife switch where 30 the sides of the clip engaging the blade of the knife switch are positioned quite closely together. These lugs are not used on the ordinary fuse clip where a fuse with a cylindrical end and body is used.

Other features and advantages, together 45 with the peculiar construction of my invention will be more clearly set forth in the following specification and claims.

In the drawings forming part of the specification,

50 Figure 1 is an end view of my fuse clip clamp in operative position.

Figure 2 is a perspective view of the same.

Figure 3 is a bottom view of the clamp.

Figure 4 is an end view of the clamp 55 using the spacing lugs to attach the clamp to a knife switch, a portion of which is illustrated in cross section.

Figure 5 is a perspective view of one of the spacing lugs adaptable to the fingers of 60 the clamp to adjust the same for different widths of engagement.

The invention includes the clamp A which is adapted to engage the arms 12 and 13 of the fuse clip B, of ordinary construction, 65 which is used to hold the metallic end of the cylindrical shaped fuse C.

The clamp A is adapted to engage the free ends of the arms 12 and 13 in a manner to firmly grip the same and cause the 70 arms to bear tightly against the surface of the fuse C so that the fuse will not jar loose in operation.

Heretofore a great deal of trouble has been experienced in using fuses where no 75 clamp such as I have illustrated is used, because the spring arms 12 and 13 are not of sufficient strength to grip the surface of the fuse C tightly and further for the reason that if the arms 12 and 13 become slightly 80 bent so that the fuse is loosely held therein, arcing occurs and the arms 12 and 13 become heated sufficiently to draw the spring temper of the same and thus the fuse is 85 destroyed or the clip itself is burned so badly that it must be replaced.

My clamp C is provided with fuse clip 90 engaging fingers 14 and 15 which have in-turned ends 16 and 17 respectively, adapted to engage the free ends of the clip arms 12 and 13 as illustrated in the drawings.

The fingers or members 14 and 15 overlap each other at 18 and are slidably connected together by the pin 19 which extends through the same and which extends into 95 and is secured to the operating cap or head 20 at 21. The pin 19 thus holds the operating cap 20 pivotally secured to the members 14 and 15 and by means of the slot 22 formed in the member 14, together with the depending flanges 23 formed on the member 14, the members 14 and 15 are held 100 slidably secured together.

The cap operating member 20 is formed 105 of porcelain or other suitable insulating material and is provided with a horizontally disposed flange 24 which extends over the members 14 and 15 in a manner to protect

the fingers of the operator when engaging the projecting lug 25 on the cap 20, thus preventing the operator's fingers from coming in contact with the metallic parts 14 and 15 of the clamp A or the contacts of the fuse clip B. This is an important feature of the invention as it provides an insulating member which is adapted to operate the clamp A in a manner so that the operator is fully protected against any short circuiting, by reason of contacting with other electrical connections in attaching or removing the clamp A, thus insuring protection to the operator's fingers and without any danger of them slipping off while operating the clamp A.

The operating cap 20 is formed with an integral cam member 26 which is provided with a beveled surface 27 which is engaged by the lugs 28 and 29 formed on the member 14 in a manner to project into engagement with the cam and to hold the cam operable and freely rotatable between the lugs 28 and 29 in the operation of the clamp A. A stop lug 30 is formed on the operating cap on one side of the cam 26 which is adapted to engage with the lugs 28 and 29 to limit the rotative movement of the same. The lug 30 projects from beneath the flange 20. In operation the clamp A is attached with its fingers or arms 14 and 15 engaging with the free ends of the arms 12 and 13 of the clip B and the operating cap 20 is rotated by engagement with the lug 25 to cause the cam 26 to operate the members 14 and 15 together or apart, so as to attach or disengage the clamp from the fuse holding clip B. The ends of the fingers of the operator engage the lug 25, resting against the flange 24 and protected from coming in contact with the metallic and electrical contacts of the fuse clip or clamp. The cam 26 moves over the center of the pivotal connection of the pin 19 with the members 14 and 15 so as to lock the same in closed position to hold the clamp firmly engaged with the clip B, thus locking it to hold the fuse rigidly in place.

In Figure 4 I have illustrated the clamp A used in conjunction with the spacing blocks or adjusting lugs 32 which are formed with recesses 33 adapted to engage with the ends 16 and 17 of the arms 14 and 15, respectively, so that the clamp A can be adjusted to engage a narrow switch clip such as D, which forms a part of the ordinary knife switch and wherein the blade 33 of the switch is firmly locked when the clamp A is attached as illustrated in Figure 4. In this use the clamp A is of the self-same design and construction, excepting that the adjusting members 32 are used on the ends 16 and 17 to permit the clamp to engage a narrower surface and to firmly clamp the blade 33 in the clip D. Obviously, different sized

spacers or lug members 32 can be used without departing from the spirit of the invention and thus my clamp can be attached readily to different sized fuse clips and switch clips so as to firmly hold the spring contacting fingers together and prevent arcing or heating of the same by reason of any loose connections.

In practice my clamp has proven to operate very satisfactorily and is adapted to lock the fuse or the blades of the switch or electrical contacts tightly together when used in a manner as I have illustrated. The adjustment of my clamp to various sized electrical connections is important and the insulated operating head formed of a single unit construction of insulating material, having the cam formed integrally therewith, is also a feature of importance and provides a practical clamping and locking means for electrical connections to insure perfect contact.

In accordance with the patent statutes I have described my invention, illustrating the best embodiment thereof, but I desire to have it understood that this is only illustrative and that the invention can be carried out by other means and applied to uses other than those above set forth within the scope of the following claims:

I claim:

1. A fuse clip clamp including a pair of members slidably secured together, a finger piece operating member and a cam formed integral therewith adapted to operate to draw said members together or spread them apart, said finger piece member and cam being formed of insulating material.

2. A fuse clip clamp including a pair of members, an operating member formed of porcelain insulating material, means for pivotally securing said operating member and said pair of members together with said members slidably in relation to each other, and cam means formed integral with said operating member adapted to operate to draw or spread said members apart.

3. A fuse clip clamp including a pair of clip engaging members, means for securing said members slidably together, an operating member formed of insulating material, and a cam formed on said operating member adapted to operate said pair of members to draw the same together or spread them apart in the operation of said fuse clip.

4. A fuse clip clamp including a pair of members adapted to engage the free ends of the fuse clip, an operating member formed of insulating material having a flange extending about the same to protect the fingers from the metallic parts of said fuse clamp, a cam formed on said operating member adapted to operate said members and means for pivotally securing said oper-

ating members with said engaging members whereby the cam can operate the engaging members slidably in relation to each other.

5. A fuse clip clamp including a pair of reciprocating arms having clip engaging ends formed thereon, an operating cap formed of insulating material including a finger protecting flange formed thereon, and means for pivotally and slidably connecting 10 said operating member and pair of clamping members together.

6. An electrical clamp for contacts including a pair of engaging members, an operating member, means for pivotally connecting 15 said operating member and clamping member together, said engaging members having a slidable connection and a cam interposed between said engaging members and said operating member formed

integrally therewith and provided with a 20 stop lug to limit the rotative movement of said operating member.

7. An electrical clamp for connectors comprising a pair of arms having engaging ends projecting therefrom, overlapping portions formed on said arms, an insulating operating member pivotally secured to said arms, a cam formed on one side of said operating member and an engaging lug formed on the other side thereof and an 25 30 annular shoulder flange interposed between said cam and operating lug in a manner to form a finger tip insulating protecting means to prevent the operator from coming in contact with the electrical connections in 35 the operation of said clamp.

EARNEST A. BACON.
